UNITED STATES PATENT OFFICE

HAROLD G. BARRETT, OF WILMETTE, ILLINOIS, ASSIGNOR TO PYRATONE PRODUCTS CORPORATION, OF CHICAGO, ILLINOIS, A CORPORATION OF ILLINOIS

RUBBING AND GRINDING MACHINE

Application filed August 17, 1928. Serial No. 300,175.

This invention is particularly adapted, though not necessarily limited in its use, for rubbing and grinding casings of golf club shafts.

Heretofore in the manufacture of golf club shafts, especially the type in which a flexible tubular casing of comparatively hard and non-metallic substance is sleeved thereupon, it has been found that the cores over which the tubing is sleeved are not always uniform, in that oftentimes the core is not perfectly round, or by reason of some other defect, with the result that heretofore the grinding and rubbing operation has resulted in removing unequal amounts of the material of the sleeve or casing at different points thereof, which is not desirable for many reasons, among others, the shaft when finished will not be properly balanced.

It is one of the objects of the present invention to overcome these difficulties and objections and to provide an improved rubbing and grinding machine of this character by means of the use of which the casing or sleeve will be uniformly ground or rubbed and the proper amount of material will be removed from the casing or sleeve regardless of the shape of the core in cross section, with the result that the sleeve or casing will be of uniform thickness about the core at any particular point in the cross section of the core and casing.

A further object is to provide an improved machine of this character in which there will be a submerged grinding or rubbing operation and at the same time the parts will be submitted to a bodily agitation to insure that the rubbing or grinding surface will be well supplied with the abrasive or grinding material or compound.

To the attainment of these ends and the accomplishment of other new and useful objects as will appear, the invention consists in the features of novelty in substantially the construction, combination and arrangement of the several parts hereinafter more fully described and claimed and shown in the accompanying drawings illustrating this invention, and in which

Figure 1 is a side elevation of a machine

of this character constructed in accordance with the principles of this invention.

Figure 2 is a vertical sectional view taken on line 2—2, Figure 1.

Figure 3 is a vertical sectional view taken on line 3—3, Figure 1.

Figure 4 is a detail sectional view taken on line 4—4, Figure 1.

Figure 5 is an enlarged detail sectional view taken on line 5—5, Figure 3, of the work to be operated upon.

Figure 6 is a detail sectional view taken on line 6—6, Figure 3, with parts omitted.

The machine consists essentially of a container having a bottom section 10 provided with a laterally projecting flange 11 around the upper edge thereof, a tubular portion 12 communicating with the bottom section, and a top or cover section 13 having a laterally projecting flange 14 which co-operates with the flange 11 on the section 10, and suitable packing material 15 is provided between the flanges 11 and 14 to form a fluid tight joint.

The sections 10 and 13 are connected together by means of a hinge 16.

Secured to the bottom section 10 is an angle iron 17 which encompasses the base, and secured to the angle irons 17 and depending therebelow are angle irons 18 which extend transversely of the bottom section 10.

Secured to the angle irons 18 are members 19 that project beyond the ends of the members 18 and are preferably reduced as at 20. Four of these members 19 are preferably provided, one at each corner of the base, and the reduced portions 20 of the members 19 project into shoes or bearing members 21, the latter being loosely connected with the portions 20.

These shoes 21 are adapted to reciprocate in guideways 22 mounted upon a suitable supporting structure 23 so that the container is adapted to be given a reciprocatory movement lengthwise of the guideways 22.

Any suitable means may be provided for accomplishing this reciprocatory movement and to that end there may be provided spaced parallel members 24 which are secured between the angle members 18 and cross members 25 which are secured between

the members 25. The members 25 are provided with openings to receive a bar or rod 26 which is formed with a shouldered portion 27 having trunnions 28 projecting laterally therefrom. Coil springs 29 encompass the bar or rod 26 on opposite sides of the head 27, one end of each of the springs resting against the head 27 and the other end against the respective bar or member 25.

10 A yoke 30 is provided which has a bifurcation 31 into which the trunnions 28 project, and this yoke is pivotally mounted as at 32 to a fixed support.

The yoke is provided with an elongated slot 33 for receiving a pin or projection 34 carried by a gear wheel 35. Meshing with the gear 35 is a gear 36 that is connected with a gear 37 for rotation therewith and the gear 37 in turn meshes with a gear 38 on the shaft of the motor 39.

15 Thus it will be seen that when the gear 35 is rotated the yoke 30 will be oscillated about its pivot 32 and thereby cause a reciprocatory movement of the container carrying the 20 shoes 21, which latter reciprocate in the guides 22.

The springs 29 form cushioning means operative at the ends of the movement of the container in the respective directions.

25 When the container is filled with a liquid and abrading material, it will be manifest that upon the bodily reciprocation of the container momentum will be imparted to the abrading or grinding material and the cushionings or springs 29 are provided for cushioning the container against shock or vibration under the influence of the abrading material as the container is reciprocated.

30 Mounted in the lower section 10 of the 40 container and extending thereacross transversely thereof, are spaced parallel rock shafts 40—41 and mounted in the upper section 13 of the container are similar spaced parallel rock shafts 42—43. Secured to the 45 rock shafts 40—42 are toothed segments 44—45 which mesh with each other, and similar toothed segments 46—47 are respectively secured to the rock shafts 41 and 43 and mesh with each other.

50 Any number of these pairs of intermeshing gears 44—45; 46—47 may be provided, but one pair is preferably arranged at each end of the respective shafts.

Carried by the shafts 41 and 43 are arms 55 48—49 and carried by the shafts 40—42 are arms 50—51. Any number of these arms may be provided, but in the present form of the invention four pairs are shown, two arms being connected with each of the shafts

60 40—41, 42—43. Connected with the arms on each of the shafts is a cross bar or member 52 and supported by each of these bars 52 are yokes or supporting members 53. Any number of these yokes 53 may be provided 65 according to the number of shafts which it

is desired to operate upon at the same time.

As shown in the drawings, the machine is adapted to simultaneously operate upon five shafts, and as the grinding and rubbing mechanism for each shaft is the same, the specific description of one will apply equally as well to them all. Supported by each of the yokes or supporting members 53 is a semi-circular member 54, two of these members being opposed to each other, each being provided with a rubbing surface 55. This surface 55 may be constructed of any suitable material such as felt, fabric or any other material suitable for the purpose and are removably secured to the respective members 54 in any suitable manner, preferably by providing a dove-tailed slot or groove 56 in the respective members 54, the slot being so shaped that when the material 55 is placed therein it will be locked against accidental displacement and at the same time the surface of the material 55 which contacts with the work 57 will be made to conform to the contour of the work.

70 The members 55 are supported by the respective yokes or supporting members 53, preferably by means of a pin 58 carried by the yokes 53 which enter elongated slots 59 in the members 54 so that the members 54 will have a pivotal as well as bodily movement with respect to the yokes or supporting members 53. A resilient element 60 preferably in the form of a leaf spring is disposed between the bottom of the yoke or supporting member 53 and the proximate face of the member 54 and these springs 60 tend normally to move the members 54 towards each other so that the grinding or rubbing surfaces 55 will grip the work 57.

75 By the provision of the slots 59 it will be manifest that when the work 57 is inserted between the co-operating grinding or rubbing surfaces 55 of the co-operating members 54, the members 54 will be adapted to assume relative positions with respect to each other to compensate the varying sizes or diameters of the work.

80 It will therefore be manifest that in the event that a tapered piece of work 57 is inserted between the members 54 of different pairs of members, the springs 60 will permit the members 54 to compensate the varying diameters of the work and will cause the work to be gripped by the rubbing surfaces with different tensions throughout the length of the work. The slot and pin connection 58—59 between the members 54 and the members 53 will permit the members 54 to rock with respect to their supports.

85 In order to vary the tension of one set of members 54 upon the work with respect to the other set, it is only necessary to rock the respective co-operating shafts 40—42; 41—43. To that end there is provided an operating lever 61 which is connected with 90

70

the shaft 40 and an operating lever 62 which is connected with the shaft 41. These levers are arranged in a suitable position on the outside of the machine and the levers are provided respectively with locking dogs 63 which co-operate respectively with toothed segments 64. The dogs are controlled by means of an operating handle 65 pivotally mounted as at 66 to the lever 62 and connected by means of a link 67 with the respective dog 68, a spring 68 being provided which tends normally to move the dog 63 into engagement with the respective ratchet 64. Thus, by adjusting either of the levers 61—62 the respective shafts 40—41 may be rocked and these shafts will through the medium of the respective intermeshing toothed segments 44—45; 46—47, cause the respective pairs of members 54 to be separated or moved closer together to vary the grip of the working surfaces 55 upon the work 57.

Thus it will be seen that a different stress or tension may be exerted upon different parts of the work 57.

The work 57 to be operated upon is fed through a suitable chuck 69 mounted upon a suitable support 70 and passes through the chuck and through an opening 71 in the wall of the lower section 10 of the casing and is then passed between the respective co-operating members 54, the forward end of the work projecting into the tubular extension 10 of the container.

In order to prevent the escape of the abrading material from the container a casing 72 is provided which surrounds the opening 71 and this casing is filled with suitable packing material 73 which encompasses the work.

Motion is imparted to the work by means of pulleys 74 connected with a portion of the chuck 69 and these pulleys are operated in any suitable manner such as by means of a flexible driving element 75 engaging over the pulleys, motion being imparted to the driving element 75 from any suitable source, not shown.

A suitable drain outlet 76 may be provided for removing the contents of the container.

It is thought that the operation of this device will be fully understood from the foregoing description, but briefly stated it is as follows. The work to be operated upon is passed through the chuck 69 and also between the co-operating pairs of members 54 with the work engaging surfaces 55 contacting with the work, the container being first filled with suitable abrasive or grinding material, preferably in a semi-liquid form.

The levers 61 and 62 are then adjusted to produce the required or desired tension between the co-operating grinding or rubbing elements. The motor 39 is then started, which will rock the yoke 30 through the medium of the gear 35 and pin and slot connec-

tion 33—34. This will impart a bodily reciprocatory movement to the container while the work 57 is being held against longitudinal movement. During this bodily reciprocatory movement of the container the work will be rotated so that both a rotary and reciprocatory grinding or rubbing operation will be performed upon the work by reason of the relative and reciprocatory movements of the work and the grinding and rubbing surfaces.

Inasmuch as the container contains a large volume of abrasive material in liquid or semi-liquid form, it will be manifest that when the container is bodily moved in one direction and this motion suddenly arrested and the direction of movement of the container reversed, there will be considerable momentum imparted to the abrasive material within the container which might, under ordinary conditions, cause considerable damage and cause a considerable "water hammer" in the machine. By the provision of the cushioning springs 29 this objection will be obviated.

It will also be manifest that with this improved machine all of the grinding and rubbing operations will be performed while the work is submerged and by the bodily reciprocatory movement of the container the rubbing surfaces 55 as well as the surface of the work 57 being acted upon, will be well supplied with the abrading material.

It will also be manifest that with the present invention one-half of the grinding and rubbing mechanism is carried by the lower section or portion of the container while the other half is carried by the upper portion or section, with the result that when the container is opened by swinging the upper section 13 about the hinge or pivot 16, the rubbing members 54 and rubbing surfaces 55 will be separated so that access may be readily had to the work. This also provides a means whereby access may be readily had to the rubbing surfaces 55 so as to remove them and replace them with other rubbing surfaces when desired.

With this improved mechanism it will also be manifest that the rubbing surfaces 55 will conform to the contour of the core upon which the sleeve or casing is placed, regardless of whether the core is regular or irregular in cross section, with the result that an equal amount of material will be removed by the grinding and rubbing operation from the surface of the sleeve or casing, to cause the latter to be of uniform thickness at any cross sectional point throughout the length of the shaft and casing.

While the preferred form of the invention has been herein shown and described, it is to be understood that various changes may be made in the details of construction and in the combination and arrangement of the several

parts, within the scope of the claims, without departing from the spirit of this invention.

What is claimed as new is:—

1. A machine of the character described embodying opposed co-operating rubbing elements between which the work is disposed, means for imparting a rotary and also a bodily reciprocatory movement to the work and said elements one with relation to the other, 10
2. A machine of the character described embodying individual means individual to the elements for maintaining the said elements and the work in engagement, and means common to said resilient means for varying at will the stress thereof. 15
3. A machine of the character described embodying a work holder, a rubbing element, means for supporting the element for bodily movement towards and away from the work and for pivotal movement with relation to the work, and means for imparting a bodily reciprocating movement and a rotary movement to the work and said element one with relation to the other. 20
4. A machine of the character described embodying a work holder, a rubbing element, a pivotally mounted support, means pivotally connecting the element with the support for bodily movement towards and away from the work and for pivotal movement with relation to the work, means for imparting a bodily reciprocatory movement and a rotary movement to the work and said element one with relation to the other, a container in which said element is disposed whereby the work and rubbing element may be maintained submerged in a grinding composition. 25
5. A machine of the character described embodying a container, means for holding the work submerged in a grinding composition within the container, a rubbing element within the container, means for imparting relative movements of the work and said element one with relation to the other to effect a grinding operation, and means for agitating the container, the last said means embodying a member slidably connected with the container, an operating element connected with said member, and springs interposed between said container and the first said member on opposite sides of the latter. 30
6. A machine of the character described embodying a container, means for holding the work submerged in a grinding composition within the container, a rubbing element within the container, means for imparting relative movements of the work and said element one with relation to the other to effect a grinding operation, means for imparting a reciprocating movement to the container, and means for cushioning the movements of the container. 35
7. A machine of the character described embodying a container, means for holding the work submerged in a grinding composition within the container, a rubbing element within the container, means for imparting relative movements of the work and said element one with relation to the other to effect a grinding operation, means for imparting a reciprocating movement to the container, and means for cushioning the relative movements of the container and the grinding composition therein, one with relation to the other. 40
8. A machine of the character described embodying a container having a body and a closure section hingedly connected together, co-operating rubbing elements one carried with each of the container sections, means for holding the co-operating elements against the work when the container is closed, and means for imparting reciprocating and rotary movements of the said element and the work one with relation to the other and when the work and elements are in contact. 45
9. A machine of the character described embodying a container having a body and a closure section hingedly connected together, co-operating rubbing elements one carried with each of the container sections, resilient means for holding the co-operating elements against the work when the container is closed, means for varying at will the stress of said elements against the work, and means for imparting reciprocating and rotary movements of the said element and the work one with relation to the other and when the work and elements are in contact. 50
10. A machine of the character described embodying a work holder, a pair of opposed co-operating rubbing elements mounted for bodily movements towards and away from the work and for pivotal movement with respect to the work on an axis intersecting the axis of the work, and means for imparting a bodily reciprocating movement and a rotary movement of the said elements and the work one with relation to the other and while the work and elements remain in contact with each other. 55
11. A machine of the character described embodying a work holder, a pair of opposed co-operating rubbing elements mounted for bodily movements towards and away from the work and for pivotal movement with respect to the work on an axis intersecting the axis of the work, means for yieldingly holding the said elements and work in engage- 60

ment, means for varying at will the stress of such engagement, and means for imparting a bodily reciprocating movement and a rotary movement of the said elements and the work 5 one with relation to the other and while the work and elements remain in contact with each other.

12. A machine of the character described embodying means for holding the work, a 10 rubbing element, a support for the element, means connecting the element to the support for bodily movement toward and away from the work, and for pivotal movement with respect to the work on an axis intersecting 15 the axis of the work, means for actuating the support to move the element toward and away from the work, and means disposed between the support and said element for yieldingly maintaining the said element in engagement with the work.

In testimony whereof I have signed my name to this specification, on this 14th day of August, A. D. 1928.

HAROLD G. BARRETT.
